Attorney

UNITED STATES PATENT OFFICE.

JOHN W. ENGELSIEPEN, OF PITTSBURGH, PENNSYLVANIA, ASSIGNOR TO UNDERWOOD TYPEWRITER COMPANY, OF NEW YORK, N. Y., A CORPORATION OF DELAWARE.

TYPEWRITING MACHINE.

Application filed June 24, 1925. Serial No. 39,176.

This invention relates to collating tables for typewriting machines, and more particularly to means for facilitating the rapid aligning and gaging of superposed work-sheets.

In certain billing operations, a ledger-sheet is introduced around the platen and is brought up over a table adjacent the front of the platen, with the side edge of said ledger-sheet gaged against a side-edge gage. A number of statement-sheets are then separately introduced and brought to position over the ledger-sheet, to be typed therewith, a carbon being introduced between the two sheets and the ledger-sheet usually remaining in the machine until all of the statements have been typed.

It sometimes occurs that the statement-sheets are sketched up or ruled in such manner that one of the edges thereof must be spaced from the corresponding edge of the ledger-sheet in order to properly register the sheets with respect to each other, and it is accordingly a feature of the present invention to provide an additional or second gage adjacent the side-edge gage of the table and against which the statement-sheets may be gaged, so as to bring the side edges thereof at a proper distance from the side edges of the ledger-sheet therebeneath.

Another feature of the invention is the provision of such additional gage, which permits free introduction thereunder of the ledger-sheet. By providing clearance for the ledger-sheet, only one table is necessary, where heretofore two tables were required. Due to the fact that the sheets may be placed one upon the other, the same table which supports the ledger-sheet also supports the statement-sheets.

Another feature of the invention is a novel means associated with the table for supporting the additional or second gage, and for permitting adjustment thereof to accommodate variations between the ledger-sheet and the statement-sheets.

Other features and advantages will hereinafter appear.

In the accompanying drawings, Figure 1 is a front view, in elevation, of

the invention, as applied to an Underwood standard typewriting machine.

Figure 2 is a cross-sectional view, in elevation, through the line 2—2 of Figure 1, and the work-sheet in typing position.

55

Figure 3 is a perspective view of the aligning plate, as applied to one of the sections of the table.

60

This invention is illustrated as applied to an Underwood standard typewriting machine, in which a platen 10 is revolvably mounted upon a platen-frame, and a work-sheet is fed around the platen by means of co-operating feed-rolls 11, the work-sheet being fed to the printing point to be struck by typebars 12.

65

According to this invention, a record or ledger sheet 13 is first inserted at the rear of the machine, leading edge first, down a rear table 14 and forwardly between the released feed-rolls 11, around the platen, and up in front thereof, past the printing point. The sheet is then laterally positioned between the upturned edges 15 of a front table comprising two plates 16 and 17 secured to 70 a supporting frame 18 by means of screws 19, the supporting frame being, in turn, fast to the side plates 20 of the platen-frame by means of screws 21.

75

The ledger-sheet is positioned relatively to the last printed item thereon, and is secured to the plate 17 by means of a clamp 22. The construction and operation of the clamp 22 may be of the character disclosed in the patent to Smith, No. 1,503,069, dated July 29, 1924.

80

For the purpose of locating a statement-sheet 23 relatively to the ledger-sheet, there is provided a novel side-edge gage including a plate 24 adjustably secured to the edge 15 85 of the plate 16 by means of screws 25. The plate 24 is provided with a downwardly-extending bent portion forming a gage 26, the bottom edge of which is slightly separated from the plate 16 to permit the insertion of the ledger-sheet therebetween. In order to facilitate the insertion of the leading edge of the ledger-sheet beneath the gage 26 of the plate 24, the bottom edge of said gage is 90 beveled or cut away at 27, to form a bell- 95

90

95

100

mouthed entrance for the sheet. In order to facilitate the handling of forms of different widths, the plate 24 is secured through slots 28, whereby it may be adjusted relatively to the edge 15 of the plate 16.

Having positioned the ledger-sheet both laterally and relatively to the printing point, ready to receive the next line of typing thereon, and having clamped the sheet 10 against the plate 17, to prevent its being accidentally shifted, the statement-sheet 23 and its associated carbon are inserted behind the ledger-sheet, over the table, and are forced around the platen, past the feed-rolls 15 and the printing point, the sheets being squared against the gage 26 of the plate 24, while being positioned relatively to the printing line to receive the first line of typing thereon.

26 The feed-rolls 11 are again rendered effective, and the clamp 22 is released preparatory to feeding the assembled work-sheet in line-space direction by means of the line-spacing mechanism 29, which is operatively mounted on a platen-shaft 30.

After typing upon the statement-sheet the matter which must be recorded upon the ledger-sheet, the platen is rotated forwardly by means of a finger-piece 31 fast to the platen-shaft 30 and the assembled work-sheet is withdrawn, whereupon the feed-rolls are again released, and a fresh ledger-sheet is inserted at the rear of the machine, and the cycle of operations is repeated.

33 Variations may be resorted to within the scope of the invention, and portions of the improvements may be used without others.

Having thus described my invention, I claim:

40 1. In a typewriting machine, the combination with a cylindrical platen, of means for collating sheets superposed one upon the other, in overlapping relation, with the side edge of the underlying sheet extending beyond the overlying sheet, including a single collating table upon which both of said sheets rest, said collating table having an outer side-edge gage for the under work-sheet, an overhanging side-edge gage, and 45 means supporting said overhanging gage with its under edge sufficiently close to said table, to enable it to gage the overlying sheet, but sufficiently separated from said table to permit the underlying sheet to be 50 passed under the overhanging gage to reach the outer gage.

2. In a typewriting machine, the combination with a cylindrical platen, of means for collating sheets superposed one upon the other, in overlapping relation, with the side edge of the underlying sheet extending beyond the overlying sheet, including a single collating table upon which both of said sheets rest, said collating table having an 60 outer side-edge gage for the under work- 65

sheet, an overhanging side-edge gage, and means supporting said overhanging gage with its under edge sufficiently close to said table, to enable it to gage the overlying sheet, but sufficiently separated from said 70 table to permit the underlying sheet to be passed under the overhanging gage to reach the outer gage, said overhanging gage being adjustable towards and from said outer gage.

3. In a typewriting machine, the combination with a platen, of a single collating table having an upturned edge providing a side-edge gage for a work-piece, and a second gage including a plate mounted adjacent said first-named gage, said plate having a downwardly-directed portion providing a gaging wall, said wall being clear of the table and having the lower edge thereof beveled to provide an entrance-mouth for the work-piece, said second gage effective to position a second work-piece resting upon said single table with the first-named work-piece.

4. In a typewriting machine, the combination with a platen, of a single collating table having an upwardly-directed edge to provide a gage for a work-piece, said upwardly-directed edge being redirected in a plane parallel with the table and providing a support, and a plate adjustable mounted on said support and having a downwardly-directed portion providing a second gage, said portion overlying the table and having the bottom edge thereof beveled to provide an entrance-mouth for the work-piece, said second gage effective to gage a second work-sheet placed upon said table in association with said first-named work-piece.

5. In a typewriting machine, the combination with a platen, of a single collating table including an edge directed upwardly to provide a gage for the side edge of a work-piece, said edge being directed at right angles to lie parallel with the table, 105 a plate having slots therein and supported upon the parallel portion, and fasteners extending through the slots and into said parallel portion, whereby to adjust said plate laterally with respect to said edge of the 110 table, said plate including a portion directed downwardly toward the table and having its lower edge spaced therefrom to provide clearance for the work-piece, said downwardly-directed portion providing a gage 115 for spacing the edge of a second work-piece from the edge of the first work-piece, both of said work-pieces being supported by said single table.

6. In a typewriting machine, the combination with a platen, of a single table having a side edge directed upwardly to provide a side gage for a work-piece, the upper edge of said gage including a portion directed 120 over the table to provide a support, a plate 125

having transverse slots therein and resting upon said support, and fasteners passing through said slots for adjustably connecting the plate to the support, said plate including a portion turned down from the body thereof and forming a second gage, the bottom edge of said downwardly-turned portion being clear of the table, said bottom

edge being also beveled toward the bottom edge of the plate to provide an entrance-mouth for the work-piece, said second gage effective to space a second work-piece away from the side edge of the first work-piece with both of said work-pieces resting upon said single table. 10

JOHN W. ENGELSIEPEN.
